UNITED STATES PATENT OFFICE.

GEORGE C. WRIGHT, OF NEW YORK, N. Y., ASSIGNOR TO E. S. HIGGINS & CO., OF SAME PLACE.

DESIGN FOR A CARPET-PATTERN.

Specification forming part of Design No. 5,605, dated March 5, 1872.

To all whom it may concern:

Specification describing a Design for Carpets, invented by Geo. C. Wright, of New York, county of New York, and State of New York.

The nature of my design is fully represented in the accompanying photographic illustration, to which reference is made.

A and B are diamond-shaped figures resting upon a mottled ground. The bands and framework of A and B are composed of two continuous and endless parallel lines. Upon the bands resting against the outer line is a "bead" composed of balls disconnected. Figure E is a leaf or scroll connected with the inside line of band, and spreading upward and downward upon the ground of A and B. Figure C is a square and quatrefoil combined between A and B, and lying upon the mottled ground D. F F are scrolls completing the frame of A and B. e e are white figures, oval in form, resting

upon which is a diamond. I prefer to color A scarlet; B, green; C, black and scarlet; e e, white; and diamond, blue.

I do not consider the colors an essential element of my design.

I am aware that carpet-patterns composed of diamond-shaped figures are not new, and do not claim that feature. The distinctive character of my design is found in the arrangement of frame-work, scrolls, and mottled ground forming my pattern.

What I claim as my invention is—

The design for carpets, composed of figures ornamented and combined with mottled ground, substantially in the manner above described.

GEO. C. WRIGHT.
